UNITED STATES PATENT OFFICE.

ALBERT MALCHOW, OF PHOENIX, ARIZONA.

WRENCH.

1,299,591.

Specification of Letters Patent.

Patented Apr. 8, 1919.

Application filed April 15, 1918. Serial No. 228,662.

To all whom it may concern:

Be it known that I, ALBERT MALCHOW, a citizen of the United States, residing at Phoenix, in the county of Maricopa, State of Arizona, have invented certain new and useful Improvements in Wrenches; and I do hereby declare the following to be a full, clear, and exact description of the invention, such as will enable others skilled in the art 10 to which it appertains to make and use the same.

This invention relates to new and useful improvements in wrenches, and particularly to gear operated wrenches.

15 One object of the present invention is to provide a novel and improved device of this character whereby the device is capable of use in right or left handed work, or for straight forward operation.

20 Another object of the present invention is to provide a novel and improved device of this character which is simple in construction, cheap to manufacture, and easy and effective in its operation.

25 Other objects and advantages will be apparent from the following description when taken in connection with the accompanying drawing.

In the drawing:

30 Figure 1 is a side elevation of a wrench made in accordance with my invention.

Fig. 2 is a side elevation of the device, one side of the casing being removed to expose the gearing.

35 Referring particularly to the accompanying drawing, 10 represents a casing which is divided longitudinally into two sections, said sections being detachably secured together by means of the screws 11. Formed longitudinally through the casing, and at one 40 side of the center thereof, is a bore 12, and disposed through this bore is a shaft 13, having on the portion within the casing a worm 14. One end of this shaft, which projects beyond the end of the casing, is formed

45 with a squared portion 15 for attachment of a socket member 16, which is adapted to engage the work to be operated upon. The other end of the shaft extends a considerable distance beyond the other end of the casing and has slidably disposed thereon a sleeve 17, said sleeve being formed with a longitudinal slot 18 for the reception of the laterally extending pin 19 carried by the said 50 shaft. Thus the sleeve is slidable longitudinally on the shaft, but rotatable with the

shaft, as will be more particularly pointed out hereinafter. The other or outer end of the sleeve is formed with a bifurcation, the inner end of which terminates in a transversely disposed circular opening 20, said bifurcation being represented by the character 21. Removably disposed through the said opening 20, is a transversely disposed bar 22, one end of which is flattened, as 55 shown at 23, for passage longitudinally through the bifurcation to permit the cylindrical portion of the bar to be disposed within said opening. By means of this bar the sleeve, together with the shaft, can be 60 rotated to turn the worm formed thereon.

Disposed transversely through the casing is a short shaft 24, the opposite ends of which project from the opposite sides of the casing as shown at 25 and 26, respectively, for the attachment thereto of the before-mentioned socket member 16, according to the side on which the device is to be engaged with the work. On the intermediate portion of the shaft 24 there is formed a 70 worm wheel or gear 27 which meshes with the before-mentioned worm of the shaft 13, whereby when said shaft 13 is rotated the motion will be communicated to the shorter shaft 24, and thus operate the socket member 75 thereon, and the work with which it is engaged. The socket member is provided with a screw 28 by means of which it is held in its secure position on the ends of the shafts. 80

Thus there is provided a device which is capable of being used to operate on a piece of work, such as a nut, which is disposed on either the right or left hand side of an object or can be operated straight in front of the operator, as will be understood, the latter case necessitating the application of the socket member to the end of the shaft 13. In the other cases the socket member is applied to one or the other end of the shorter 90 shaft 24. On the shaft 13, at each side of the worm 14 there is disposed a friction washer 14'. 95

By reason of the slideable sleeve 17, the shank of the device is thus rendered capable of being lengthened or shortened to permit the tool to reach different distances to suit the character of the work and the desires of the user. 100

What is claimed is:

110 A wrench including a casing, a shaft disposed longitudinally through the casing and

having a worm formed thereon and within the casing, a transverse shaft disposed through the casing and having a worm wheel meshing with the said worm, a sleeve 5 slideable on the first-named shaft and rotatable therewith, a work engaging socket arranged for detachable engagement with the end of the first-named shaft and with the ends of

the last-named shaft, and means for rotating the said sleeve.

In testimony whereof, I affix my signature in the presence of two witnesses.

ALBERT MALCHOW.
